CONTACTOR FOR MOISTURE METERS

Raymond Speers Hart, Brooklyn, N. Y.

Application June 19, 1941, Serial No. 398,709

4 Claims. (Cl. 175—183)

This invention relates to improvements in contactors for moisture meters and particularly to contactors for measuring the moisture of granular materials.

Heretofore it was necessary, when it was desired to measure the moisture content of such materials as flour, etc., to apply the slow and cumbersome method of the oven-and-scale whereby a sample is weighed before and after drying and the moisture content is computed as a percentage of the total weight from the difference in weight before and after drying. It has been found, however, that by the use of a special contactor it is possible to quickly measure the moisture content by the conductivity of the material using a meter such as disclosed in my Patent No. 2,183,333 dated December 12, 1939. The present invention serves this purpose as it will be shown hereinafter and it furnishes new and unique means for the quick determination of the moisture as well as for the easy handling of the materials to be tested.

An important object of the invention is to provide a contactor with two electrodes, one of which is well insulated from the other, and which may be connected to a sensitive meter.

Another object of my invention is to provide a contactor having one electrode removable and formed in the shape of a sampling spoon wherein the sample to be tested may be placed by dipping the spoon directly into, for instance, a bag of flour or other container.

A further object of my invention is to provide a contactor of the lever type providing means for obtaining repeatedly the same pressure between the electrodes and being easily operable by the handle of the one electrode.

Other objects and advantages of the invention will be apparent during the course of the following description.

In the accompanying drawing, forming a part of this specification, and in which like numerals are employed to designate like parts throughout the same,

Figure 1 is a side elevation of a moisture meter contactor embodying my invention,

Figure 2 is a view along line 2—2, in Figure 1.

Figure 3 is a plan view of the combined sample spoon and electrode,

Figure 4 is a plan view of the compound lever, and,

Figure 5 is a section along line 5—5 in Fig. 1.

In the drawing, wherein for the purpose of illustration, is shown a preferred embodiment of my invention, the numeral 10 designates the

main body of the contactor which is made in the form of a C-clamp. The lower portion of the body 10 carries an integral mounting block 11 with holes 12 for mounting to the instrument or to any other suitable object. The upper end of the C-clamp has a cylindrical hub 13 which is drilled and tapped for a vertical screw 14 with the head 15. To the head 15 is fastened an insulator 16, preferably of a material such as "Lucite" or similar insulating material having an extremely low surface absorption of moisture and, therefore, an exceedingly high insulation resistance. To the bottom side of the insulator 16 is fastened a metal disc 17 having a small hub 18 and being free to swivel on the fastening screw 19. The metal disc 17 forms the one electrode from which a wire is connected to the grid of a sensitive vacuum tube voltmeter instrument such as disclosed in my patent mentioned supra.

The other electrode consists of the cup-shaped metallic part 20 which is fastened on a bar 21 and which has a transverse groove 22 which fits over the nose 23 of the compound lever 24. The removable electrode 20 with arm 21 is shown in plan view in Figure 3 and the lever 24 is shown in plan view in Figure 4. The lever 24 is forked at one end and its two forked ends 25 and 26 are pivoted to the C-clamp 10 by the pins 27.

The lower jaw of the C-clamp has a cylindrical body 28 which is bored out as shown in Figure 5, in cross-section. The hollow section of the cylindrical portion 28 contains the vertical push rod 29 which is journaled in a bearing in the upper end of the body 28 and also in a bearing in the bottom nut 30. The push rod 29 has a fixed shoulder 31 and between this shoulder 31 and the bottom nut 30, is located a heavy coil spring 32. The tension of the spring 32 may be adjusted by turning the bottom nut 30 which has two holes 33 for the insertion of a wrench.

The operation of my invention is as follows:

Once the tension of spring 32 is adjusted and the meter is calibrated for a certain granular material, it is only necessary to connect disc 17 to the grid terminal of the meter while the body of the contactor is connected to the ground terminal. The lower contactor cup with handle 21 may then be removed and dipped into the material to be tested whereby the cup is filled with a suitable sample. The handle 21 with cup 20 is again inserted into the contactor and the handle 21 is brought downward with a pressure directed, as shown by the arrow in Fig. 1. By applying a sufficient pressure on handle 21, the cup 20 will be pressed up against the disc 17 and the handle

21 together with the lever 24 will form a compound lever arrangement which will force the end of the lever 24 down and will move the push rod 29 with shoulder 31 down against the pressure of spring 32. After a comparatively small movement of the lever 21, the pressure between disc 17 and cup 20 is then that which is caused by the spring 32 and the pressure will not change very much regardless of whether the lever is moved a little more or less as long as the spring 32 is fully engaged. At this point the meter reading is made and consistent readings will be possible because the pressure is maintained at a figure which will be the same repeatedly for every measurement made because of the pre-loading of spring 32 and due to the fact that said spring is just barely engaged. In this manner a substantially constant pressure is obtained, provided lever 21 is moved only until 31 just leaves stop 28 so that full spring pressure is obtained.

In addition to flour and similar materials, there are a number of other industrial products which may be tested similarly and to great advantage by the use of this contactor. Due to the fact that quite often a great number of tests have to be made at one time, the present contactor affords the possibility of making quick determinations without many and elaborate operations.

It is to be understood that the form of my invention, herewith shown and described, is to be taken as a preferred example of the same, and that various changes in the shape, size and arrangement of parts may be resorted to without departing from the spirit of my invention or the scope of the subjoined claims.

Having thus described my invention I claim:

1. In an instrument for testing comminuted material, a frame having a depending insulated electrode, a spring controlled push rod below the electrode, means pivoted on said frame and having a portion resting on said rod, and manipu-

lable means adapted to rest on the first means and having a cup-shaped electrode for holding material below and in contacting relation with the first electrode.

5. In an instrument for testing comminuted material, a frame having a depending insulated electrode, a spring controlled push rod disposed below the electrode and having a rounded top, a lever pivoted on said frame and resting on said

10 top, and a manipulable member including a handle and having an electrode forming a receptacle for holding material to be tested below and in contacting relation with the first mentioned electrode, said member adapted to be removably seated on the lever.

3. A testing device for comminuted material comprising in combination a frame having thereon an upper depending insulated electrode, a lower cylinder rigid with the frame and having

20 therein a spring controlled rod with an upper end below the electrode, a normally horizontal lever pivoted on the frame and resting on said end, the lever providing a space below the electrode, a manipulable member including a handle and having

25 a portion for entering said space, and another electrode forming a receptacle for material and carried by said portion below the upper electrode.

4. A testing device for comminuted material

30 comprising in combination a frame having upper and lower arms and a lateral attaching member, an insulated electrode carried by the upper arm, a housing having top and bottom apertures and rigid with the lower arm, a rod movable in the

35 apertures and having an upper projecting end, spring means controlling said rod, a lever pivoted on the frame and resting on said end, manipulable means removably seated on the lever, and an electrode forming a sampling container and disposed on the last mentioned means below and adjacent the upper electrode.
